UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,330,619.

Specification of Letters Patent.

Patented Feb. 3, 1920.

Application filed June 7, 1916. Serial No. 102,184.

To all whom it may concern:

Be it known that I, JOHN ERICKSON, a citizen of the United States of America, and a resident of Chicago, county of Cook, and 5 State of Illinois, have invented certain new and useful Improvements in Measured-Service Telephone Systems, of which the following is a specification.

My invention relates in general to measured service telephone systems but is concerned more particularly with measured service telephone systems of the automatic type in which the connections are established by automatic switches controlled by 15 the individual subscribers.

In systems of the above character the measured service equipment usually comprises either coin collecting devices or meters. Whatever the device used, it ordinarily 20 performs its function but once for each successful originating call made over its associated line. If a coin collecting device is used, one coin or token is collected for each call; if a meter, one call is registered 25 against the calling subscriber when the called party answers.

In every exchange there are certain subscribers who are prone to take advantage of the ordinary measured service system by 30 prolonging their conversations to an undue length, and it is evident that where the charges are based on a certain rate per conversation, regardless of its length, they may do so with impunity. It is desirable, therefore, to provide in connection with a measured service system, means of some kind for 35 limiting the length of conversations, both to protect the telephone company from impositions on the part of the subscribers, and to 40 secure a more equitable distribution of the charges.

The present invention provides an apparatus whereby after a predetermined time interval a distinctive tone may be thrown 45 on a connection to warn the talking subscribers that their conversation has continued for the maximum time allowed and that additional toll must be collected. In case the subscribers persist in holding the connection, agencies are brought into play 50 shortly afterward which result in the collection of an additional charge from the calling subscriber.

The particular means which I employ in 55 accomplishing the foregoing and other use-

ful ends will be fully described hereinafter, reference being had to the accompanying drawings, in which Figures 1 and 2 show diagrammatically a complete circuit connection between a calling substation A and 60 a called substation A' in a system embodying the principles of my invention, while Figs. 3 and 4 illustrate certain mechanical parts of the conversation limiting apparatus. The central office apparatus used in 65 establishing the complete connection above referred to comprises the individual line switch C (Fig. 1) and the connector switch F (Fig. 2). For the purpose of simplifying the drawings and the explanation, the selector switches, which are understood to be included in a system of any size, are omitted. 70

Referring now to Fig. 1, the substation A may be of any suitable or approved type although as shown it is similar to the substation shown in the British patent to Martin, No. 1419 of 1910. Among other details it comprises the receiver 2, transmitter 3, induction coil 4, hook switch 5, ringer 6 and condenser 7. Being an automatic substation 80 there is also provided a calling device comprising essentially a pair of impulse springs 8 and 9 controlled by the impulse wheel 10 through the medium of a finger hole dial (not shown). 85

Associated with the substation A is shown diagrammatically a coin collecting device which comprises among other details a polarized relay 12 in series with one of the line conductors, a set of contact springs 13 90 controlled by the relay 12 and adapted to render the substation A inoperative for talking purposes, and suitable coin controlled means including a coin chute (not shown) for restoring the substation to operative 95 condition. A similar coin collecting device has been shown and described in U. S. Letters Patent #1,062,387, granted to me on May 20, 1913, and consequently no extended description will be given herein. 100

The line conductors 14 and 15 of the substation A are connected at the exchange to the individual line switch C which is of the general type of line switch disclosed in the British patent to James, #26,801 of 105 1906; being, however, of the particular type shown in U. S. Letters Patent #1,078,690, granted Jan. 17, 1912, to Frank Newforth. Since line switches of the above type are well known and form no part of my invention 110

an extended description will not be given. It will suffice to say here that through the medium of line switch C the line of substation A when calling is given access to a plurality of trunk lines extending to connector switches.

The master switch D is of the general type of master switch disclosed in the above mentioned British patent to James, #26,301 10 of 1906; being, however, more nearly of the particular type disclosed in the British patent to Martin, #1419 of 1910, also previously referred to. As is well known, the function of the master switch is to maintain the plungers of all idle line switches in position before the terminals of an idle trunk line.

One of these trunk lines is indicated in the drawings by reference characters 40, 41, 20 and 42 and terminates in the connector switch F (Fig. 2), which is of the general type of connector switch disclosed in U. S. Letters Patent #815,176, granted March 13, 1906, to Keith, Erickson, and Erickson; being, however, of the particular type disclosed in the British patent to the Automatic Telephone Mfg. Co., #2270 of 1914. A connector switch of the foregoing type may be given access to a group of subscribers' 30 lines and is operable in response to digits of a called number to establish connection with any line in the group.

The substation A' and the line switch C' may be similar, respectively, to the substation A and the line switch C, which have already been briefly described.

Considering now the conversation limiting apparatus shown diagrammatically in Fig. 1, it will be seen that the upper trunk conductor 40 includes the right hand winding of the electro-polarized relay 45, while both conductors 40 and 42 include spring contacts of the reversing relay 49. Each trunk line is provided with a pair of similar relays, whose operation will be fully described hereinafter. With each pair of relays is associated a device comprising, in the case of the trunk line shown, the solenoid 60, plunger 61, and contact springs 56-59, inclusive. The solenoids associated with a group of trunk lines are preferably mounted together, as shown in Fig. 3, in order that their plungers may be controlled by a common time mechanism. A soft iron mounting plate 63, bent to the shape shown in Fig. 4, is secured in suitable manner to the support 66. Each of the solenoids 60 is provided with a heel piece 67 through the medium of which it is secured to the mounting plate 63. A soft iron roller 62, fitting loosely in the curved portion of the mounting plate 63, is carried by the shaft 65, which in turn is rotatably supported by bearings at each end of the mounting plate, one of these 65 bearings being indicated by reference

character 64. Each solenoid is provided with a plunger 61 which fits loosely in a brass sleeve or tube which carries the solenoid winding and which extends up through the heel piece 67 to prevent sticking between the plunger and heel piece. The parts are so disposed that the solenoid plungers 61 are in light contact with the roller 62. The shaft 65 is constantly rotated at a slow rate by clock work or other suitable means (not shown). The several sets of contact springs controlled by the solenoid plungers are not shown in Figs. 3 and 4 but it will be understood from a consideration of the diagrammatic showing in Fig. 1 that each set is 80 suitably mounted above its associated plunger in position to be controlled thereby, all of which will appear more clearly in the description of the operation which is to follow.

To supply current for operating and talking purposes I have shown a battery B having its positive pole grounded. The auxiliary apparatus comprising the ringing current generator R, the ringing interrupter I, 90 and the busy signaling machine Q are of the ordinary type and perform the same functions as the same named pieces of apparatus in other automatic exchanges.

The apparatus having been briefly described, I will now proceed to a description of the operation of the same. Inasmuch as a great deal of the automatic equipment is old and well known, having been fully described in the publications previously referred to, the operation of such equipment will be described in a more or less general manner.

Referring to Fig. 1, when the calling subscriber at substation A removes his receiver 105 to initiate the call, an energizing circuit is completed over the line conductors 14 and 15 for the line relay 16 of the line switch C. Upon attracting its armature, the line relay 16 closes a circuit for the pull-in winding 110 17. Upon energizing, the pull-in winding operates both the plunger arm 21 and the cut-off armature 22; the former through the medium of its plunger (not shown) forcing the bank springs 30-33, inclusive, into engagement, respectively, with contacts 34-37, inclusive; and the latter disconnecting the line conductors 15 and 14, respectively, from ground and from the line relay 16. By the engagement of bank springs 30 and 33, respectively, with contacts 34 and 37, the line conductors 14 and 15 are extended via trunk conductors 40 and 42 to the double-wound line relay 100 of the connector F.

The line relay 100 is accordingly energized over the loop circuit including substation A and, upon attracting its armature, closes a circuit for the slow-acting release relay 101. Upon energizing, the release relay 101 completes a holding circuit for the 130

line switch C which may be traced as follows: ground at G^6 , contact springs 119, conductor 41, contact 35, bank spring 31, and holding winding 18 to battery B. Since 5 the line relay 16 is slow-acting, it retains its armature to maintain the pull-in winding energized until after the above holding circuit has been established. A branch of the holding circuit extends from bank spring 31 10 by way of conductor 19 to multiple test contacts in the banks of connector switches having access to the line of substation A where by a ground potential on these test contacts the said line is made busy. By the engagement 15 of bank spring 32 with contact 36 the master switch D is operated in well known manner to advance the plungers of all the remaining idle line switches into position before the terminals of the next idle trunk 20 line.

It should be noted at this point that the trunk conductor 40 includes the winding 47 of the electro-polarized relay 45. Current is also flowing in the polarizing winding 46 25 from the grounded conductor 41 to the battery B. Neither winding of relay 45 is sufficiently powerful of itself to operate the armature, but it requires the combined effect of both windings. Since at this time the 30 magnetizing effects of the two windings are in opposition the relay 45 is not operated. At the substation A the polarized relay 12, being in series with one side of the line, is energized and operates its armature to the 35 position shown in the drawing.

The foregoing operations whereby the line conductors 14 and 15 have been extended through to the line relay 100 of the connector F have taken place in response to the removal 40 of the receiver at substation A. The calling subscriber may now manipulate his dial in accordance with the first digit of the desired number, thereby separating momentarily the impulse springs 8 and 9 a number 45 of times and interrupting each time the energizing circuit of the line relay 100. As a result of these interruptions of its circuit the line relay 100 is deenergized a corresponding number of times and sends at each deenergization an impulse from ground G^7 to the slow-acting relay 103 and the vertical magnet 104 in series, side switch wiper 115 being in its first position. The vertical magnet in response to these impulses steps up the 50 switch shaft until the wipers 130, 131, and 132 stand opposite the horizontal level of bank contacts in which is located the terminal of the line of substation A'. The relay 103 is energized in series with the vertical magnet and, being slow-acting, retains its armature during the series of impulses to maintain a circuit from ground G^6 to the private magnet 107. At the end of the series 55 of impulses the relay 103 deenergizes and breaks the circuit of the private magnet,

which latter controls the side switch wipers to advance them to their second position in the usual manner.

The subscriber at substation A may now operate his dial in accordance with the final 70 digit of the required number, resulting as before in deenergizations of the line relay 100. Now, however, side switch wiper 115 being in its second position, the line relay sends impulses to the slow-acting relay 103 75 in series with the rotary magnet 105. The rotary magnet operates in response to these impulses to rotate the wipers 130, 131, and 132 until they rest, respectively, upon bank contacts 133, 134, and 135, these contacts 80 forming the terminal of the line of substation A' in the bank of connector F.

The relay 103 and the private magnet 107 are energized during the last series of impulses as before, the latter disconnecting 85 the line wipers during rotation and controlling the side switch wipers at the end of the series of impulses to advance them to their third position, it being assumed that the line of substation A' was idle when 90 called.

As side switch wiper 116 comes into engagement with its third position contact point, a circuit is completed for the holding winding of line switch C' as follows: 95 ground at G^{10} , side switch wiper 116 (in third position), wiper 131, bank contact 134, and holding winding 18' to battery B. By the attraction of the cut-off armature 22' the line conductors of substation A' are disconnected, respectively, from ground and from the line relay 16'. It is understood that the holding winding 18' is not sufficiently powerful to operate the plunger arm 21'. Ground at G^{10} also extends to multiples 100 of bank contact 134 in the banks of other connectors of the group, thereby making the line of substation A' busy to other calls. By the engagement of side switch wipers 117 and 118 with their third position contact points the connection between the calling and called lines is completed. By the engagement of side switch wiper 115 with its third position contact point, a circuit is completed for the ringing relay 108 in series 110 with the interrupter I, whereby ringing current is projected intermittently out over the line of substation A' to operate the signal in bridge thereof. 115

The subscriber at substation A has now 120 established the desired connection with substation A' and the bell at the latter substation is being rung to attract the attention of the called subscriber. When the called subscriber removes his receiver from the hook a circuit is completed for the double wound back bridge relay 102 in the well known manner. Upon attracting its armature, relay 102 closes a circuit for the ring cut-off relay 106 which relay locks itself to 125 130

4
ground at G^1 and also opens the circuit of the ringing relay 108, thereby stopping the ringing operation.

As a further result of the energization of the back bridge relay the incoming trunk conductors 40 and 42 are reversed as regard their connection to the windings of the line relay 100. The direction of current flow in the calling line is therefore reversed with several important results which will now be described. At the substation A the polarized relay 12 reverses the position of its armature thereby rendering the telephone instrument inoperative for talking purposes by closing the springs 13. The telephone is not completely disabled, however, for although the transmitter is short-circuited, the receiver is only shunted by a resistance so that the calling subscriber will be able to tell whether or not he has the right number. Finding that the desired connection has been obtained the calling subscriber now restores his telephone instrument to operative condition again by depositing one or more coins in the usual manner and is then able to converse without further effort. The complete talking circuit has been drawn in heavy lines and will be apparent without additional description.

The talking connection between the calling and called subscribers having been established, it is to be presumed that the operation of the time limit device associated with the trunk line used was initiated also, and such is the fact. When the direction of current flow in the calling line was reversed upon the response of the called subscriber, not only was the polarized relay 12 at the substation A operated with the results mentioned, but at the exchange the electro-polarized relay 45 is enabled to attract its armature, since its two windings now assist each other. When its armature is fully attracted the winding 47 is short-circuited and the relay is maintained in operated position by the winding 46 alone. An energizing circuit for the solenoid 60 may now be traced as follows: ground at G^2 , contact springs 54 and 55, contact springs 51 and 50, and winding of solenoid 60 to battery B. As a result of the magnetic field set up by current in the solenoid the plunger 61 and the roller 62 attract each other, and since the roller is rotating the plunger 61 will be slowly raised up through the center of the solenoid by magnetic friction. After a certain predetermined time interval the plunger 61 forces spring 59 into engagement with spring 57. The spring 58 is adjusted to follow spring 57 for a short distance so that for a few seconds a tone from the buzzer M is projected out over the connected lines to inform the subscribers that their conversation has nearly reached the limit. Upon further movement of the plunger 61 the contact

springs 56 and 57 come into engagement, thereby closing the following circuit: ground at G^3 , secondary winding of the buzzer M, contact springs 59, 57, and 56, and winding of slow-acting relay 49 to battery B. Upon attracting its armature, relay 49 reverses the trunk conductors 40 and 42 in an obvious manner and near the end of its stroke separates the contact springs 54 and 55, thereby breaking the energizing circuit of solenoid 60. The plunger 61 immediately falls by gravity to its normal position and breaks the energizing circuit of relay 49. Since relay 49 is slow-acting it retains its armature an instant in order to insure the complete retraction of the plunger 61. When relay 49 finally deenergizes, the trunk conductors 40 and 42 are connected straight through again, the energizing circuit of the solenoid 60 is again completed, and the plunger 61 begins its ascent up through the core of the solenoid again.

It will be understood that the purpose of the momentary energization of relay 49 after a predetermined time, is to effect by a reversal of the line current the operation of the polarized relay 12 at the calling substation, whereby the telephone instrument is again rendered inoperative for talking purposes. When the calling subscriber hears the tone from the buzzer M on the line, he at once gets another coin ready to deposit, provided, of course, that he wishes to continue the conversation. Being thus warned in advance but little time need be lost and consequently the interruption of the conversation is not seriously objectionable. Of course, the deposit must not be made until after the tone leaves the line (and relay 49 has restored) or the coin would be wasted. The time limit device at the exchange continues to operate as long as the connection is held, momentarily reversing the line current at intervals and requiring each time an additional deposit by the calling subscriber.

When the conversation is finished both subscribers will hang up their receivers. By the replacement of the receiver at substation A the energizing circuit of line relay 100 is broken. Upon deenergizing, the line relay opens the energizing circuit of the slow-acting release relay 101, which latter relay, upon deenergizing, closes a circuit for the release magnet 109 and also removes ground from the holding circuit extending back to line switch C. By the closure of the release magnet circuit the connector F is restored to normal position in the usual and well known manner. By the removal of ground from the holding circuit the holding winding 18 of line switch C is deenergized and the plunger is withdrawn from the bank. As a further result the relay 45 is deenergized, thereby stopping the operation of the time limit apparatus. All the equipment used will then

have been restored to normal in readiness for other calls.

It will be seen from the foregoing that I have devised a simple and efficient apparatus for use in connection with a measured service system whereby conversations may be limited to a definite time and additional charges collected on all conversations which exceed the time limit.

10 While I have found it convenient in explaining my invention to show a certain specific embodiment thereof, I am well aware that changes may be made in order to adapt the same to other types of measured service systems. I do not, therefore, wish to limit myself to the exact form shown but desire to include and have protected by Letters Patent all forms and modifications of my invention which may come within the 15 scope of the appended claims.

What I claim as my invention is:

1. In a telephone system, a calling and a called line, means for connecting said lines, a reverse current controlled device for rendering the calling telephone inoperative for talking purposes, means comprising a coin collecting device for restoring the calling telephone to operative condition, a battery for supplying talking current, a relay for 20 reversing the current flow in the calling line to require the deposit of a coin before conversation can begin, and a second relay for momentarily reversing the current flow in the calling line again after a predetermined 25 time to require the deposit of another coin.

2. In a telephone system, a calling and a called line, means for connecting said lines, a reverse current controlled device for rendering the calling telephone inoperative for 30 talking purposes, means comprising a coin collecting device for restoring the calling telephone to operative condition, a battery for supplying talking current, a relay for reversing the current flow in the calling line 35 to require the deposit of a coin before conversation can begin, a second relay for momentarily reversing the current flow in the calling line again after a predetermined time to require the deposit of another coin, a device 40 for producing an audible tone, and means for connecting said device with the calling line whenever an additional coin is required 45 to notify the calling subscriber.

3. In a telephone system, a calling and a 50 called line, means including an automatic progressively movable switch for connecting said lines, a reverse current controlled device for rendering the calling telephone inoperative for talking purposes, means comprising a coin collecting device for restoring 55 the calling telephone to operative condition, a battery for supplying talking current, a relay for reversing the current flow in the calling line to require the deposit of a coin 60 before conversation can begin, a second re-

lay for momentarily reversing the current flow in the calling line again after a predetermined time to require the deposit of another coin, and means for notifying the calling subscriber when an additional coin 70 is to be deposited.

4. In a telephone system, a calling and a called line, automatic switches at the exchange for uniting said lines in a talking circuit comprising two inductively connected 75 sections, a device at the calling substation for assessing a charge against the calling subscriber at the beginning of conversation, and automatic mechanism included in the calling section of the talking circuit for controlling said device to assess an additional charge 80 at intervals thereafter.

5. In a telephone system, a calling and a called line, automatic switches at the exchange for uniting said lines in a talking 85 circuit comprising two inductively connected sections, a device at the calling substation for assessing a charge against the calling subscriber at the beginning of conversation, automatic mechanism included in the calling 90 section of the talking circuit for controlling said device to assess an additional charge at intervals thereafter, and a signaling device adapted for connection to the calling line under control of said mechanism to notify 95 the calling subscriber when an additional charge is to be assessed.

6. In a telephone system, a calling and a called line, means for connecting said lines, a device at the substation requiring the deposit of a coin by the calling subscriber at the beginning of conversation, and time mechanism including a frictionally driven movable element for controlling said device to require the deposit of additional coins at 100 intervals thereafter.

7. In a telephone system, a calling and a called line, means for connecting said lines, a device at the substation requiring the deposit of a coin by the calling subscriber at 110 the beginning of conversation, mechanism at the exchange for controlling said device to require the deposit of an additional coin, a continuously operating power shaft, and means including an electromagnetic clutch 115 for causing said shaft to actuate said mechanism at intervals during the conversation.

8. In a telephone system, the combination with connecting means comprising a plurality of trunk lines, of mechanism associated 120 therewith for dividing conversations into periods of predetermined length, said mechanism comprising a driven shaft, and an electromagnetic clutch controlled device associated with each trunk line and operated 125 from said shaft for notifying connected subscribers when the said periods have expired.

9. In a telephone system, the combination with connecting means comprising a plural- 130

6
ity of trunk lines, of mechanism associated therewith for dividing conversations into periods of predetermined length, said mechanism comprising a common power source, 5 and a device associated with each trunk line and mechanically operated from said common source for notifying connected subscribers when each period has expired.

10. An electric circuit switch in combination with a controller therefor, said con-

troller having a plunger, a wheel associated with said plunger, means for bringing said plunger and wheel into engagement, means for rotating said wheel while thus in engagement with the plunger to move the 15 latter, and a toll assessing device controlled over the said circuit.

Signed by me at Chicago, Cook county, State of Illinois, this 1st day of June, 1916.

JOHN ERICKSON.
